UNITED STATES PATENT OFFICE.

CARL HANER, JR., OF BALTIMORE, MARYLAND, ASSIGNOR TO U. S. INDUSTRIAL
ALCOHOL CO., A CORPORATION OF WEST VIRGINIA.

FURNACE.

1,342,958.

Specification of Letters Patent.

Patented June 8, 1920.

Application filed November 22, 1917. Serial No. 203,402.

To all whom it may concern:

Be it known that I, CARL HANER, Jr., of Baltimore, in the State of Maryland, have invented a certain new and useful Improvement 5 in Furnaces, and do hereby declare that the following is a full, clear, and exact description thereof.

My invention relates to furnaces adapted to be used for many different purposes, but 10 it is applicable especially to furnaces used for drying or baking distillery waste or slop.

The object of my invention is to provide a furnace of an advantageous character and which is so arranged as to distribute the 15 heat effectively therein.

A further object of my invention is to provide a furnace arranged to distribute the heat uniformly therein and which is heated by oil burners located at one end 20 of the furnace.

Further objects of my invention will appear from the detailed description thereof contained hereinafter.

While my invention is capable of embodiment in many different forms, for the purpose of illustration I shall describe only one form of my invention in the accompanying drawings, in which—

Figure 1 is a plan view of a furnace made 30 in accordance with my invention;

Fig. 2 is a vertical section of the main portion of the same;

Fig. 3 is a part elevation and part transverse section of the same;

Fig. 4 is a longitudinal vertical section, 35 showing the arrangement of the oil burners at one end of the furnace;

Fig. 5 is a transverse vertical section of the same;

Fig. 6 is an end elevation, showing the 40 location of the oil burners; and

Fig. 7 is an end elevation, showing one of the cars adapted to convey the material to be heated into the furnace.

In the drawings, I have shown a plurality of air-blast oil burners 1, located in 45 openings 2 in a front wall 3, communicating with a downwardly-inclined passageway 4. The passageway 4 communicates with a longitudinal passageway 5, located between the sides of two walls 6, having a cover plate 7, for example of sheet iron, and a lower lining 8. The iron plate 7 is provided at 50 intervals with a plurality of openings 9, which increase in size from the inlet end

of the passageway 5 to the outlet end thereof, the purpose being thereby to admit an increasing amount of the products of combustion from the passageway 5 to the space above plate 7, so as to bring about 60 a uniform distribution of the heat therein.

At intervals along the passageway 5 there are provided a plurality of pillars 10, which support the plate 7 and provide an adequate support for a pair of rails 11, carrying cars 65 12.

Each car 12 has a number of racks 13, supported upon uprights 14, so as to receive a plurality of pans or trays 15, which are used for receiving the distillery waste or slop to be dried or baked. The space above 70

the plate 7 is inclosed with side walls 16 and a roof 17. At the two ends thereof there are located, respectively, pairs of swinging doors 18 and 19. Products of combustion from the oil burners 1 pass from the pas- 75

sageway 4 into the chamber 5, and thence through the openings 9 into proximity to the cars 12, after which they pass out through 80

a pipe 20, which leads out through the roof 17, and then downwardly to an exhaust fan 85 24, driven by any suitable source of power, through the agency of a pulley 25 connected to said fan. The products of combustion are exhausted from the fan 24 through a

pipe 26, which leads to a stack 27.

In the operation of my invention, a plurality of the cars 12, having been provided with pans 15 filled with the distillery waste or slop, are run into the furnace on the tracks 11 and the doors 18 and 19 are 90

closed. Meantime, the furnace will have been heated by the series of oil burners, from which products of combustion pass 95

forwardly through the passageway 4 and chamber 5 and through the openings 9. Because of the progressive increase in size of the openings 9, the furnace is heated in a uniform manner. The products of combustion, after leaving the cars 12, pass out

through the pipe 20 to the fan 24, out 100 through the stack 27. The heating is continued in this manner until the material in the pans 15 has been dried or baked to the desired extent. Thereupon the doors 19 are

opened and the cars 12, carrying the material which has been completely subjected to the heat treatment, are drawn out of the furnace. The doors 19 are then closed and the doors 18 opened to introduce additional 105 cars to take the place of those removed, 110

whereupon the doors 18 are closed and the heat treatment continued. In this way, the heating of the material may be carried on progressively and in a substantially continuous manner. At the same time, the heat treatment will have been substantially uniform, so that the material in the pans 15 will not have been subjected to any excessive degree of heat.

10 While I have described my invention above in detail, I wish it to be understood that many changes may be made therein without departing from the spirit thereof.

I claim:

15 1. A furnace having a heating chamber, substantially level rails extending therethrough and means for heating the chamber comprising a conduit for the hot products of combustion below the heating chamber, 20 the inlet end of which is downwardly inclined, and means for uniformly distributing the heated products of combustion in said heating chamber.

2. A furnace having a heating chamber, substantially level rails extending therethrough, and means for heating the chamber comprising a conduit for the hot prod-

ucts of combustion below the heating chamber, the inlet end of which is downwardly inclined, a plurality of openings for uniformly distributing the heated products of combustion in said heating chamber and a fan at one end of said heating chamber for withdrawing the products of combustion.

30

3. A furnace having a heating chamber, rails extending therethrough, means for heating the chamber comprising a conduit for the hot products of combustion below the heating chamber, the inlet end of which is downwardly inclined, a series of oil burners at one end of said conduit and a plurality of openings of progressively increasing size so disposed in the bottom only of said heating chamber as to uniformly distribute the heated products of combustion in said heating chamber.

35

In testimony that I claim the foregoing I have hereunto set my hand.

CARL HANER, JR.
